Patented Oct. 3, 1972

224,878

VALET RACK

Robert O. Memmel, P.O. Box 6, Okauchee, Wis. 53069

Filed Nov. 4, 1970, Ser. No. 25,825

Term of patent 7 years

Int. Cl. D6—08

U.S. Cl. D6—247

FIG. 3

FIG. 4

FIG. 5

FIG. 6

FIG. 1 is a top view of a valet rack showing my new design.

FIG. 2 is a front elevational view.

FIG. 3 is a bottom view.

FIG. 4 is a left side elevational view.

FIG. 5 is a right side elevational view.

FIG. 6 is an elevational view taken along section line 6-6 on FIG. 2 of the drawings to illustrate the relative shape of the respective parts thereof.

I claim:

The ornamental design for a valet rack, as shown.
